UNITED STATES PATENT OFFICE

LORENZO ARRANZ, OF NEW YORK, N. Y.

MASSAGE DEVICE

Application filed June 4, 1928. Serial No. 282,616.

This invention relates to improvements in massage devices.

The primary object of the invention resides in a massage device which may be strapped to the wrist and grasped by the hand of an operator to manually actuate the device and guide the same over the surface to be massaged, and by the use of which the surface may be effectively massaged.

Another object of the invention is to provide a massage device embodying a cylindrical rotary massage element having vacuum cups on the exterior thereof which are compressed as the cups engage the surface to be massaged, to create a suction action upon the skin by which the tissues are exercised or stimulated and the circulation of the blood flow of the human body induced.

A further object is the provision of a massage device embodying a rotatable rubber cylinder having vacuum cups arranged circumferentially therearound on the exterior, and inwardly extending heads behind the vacuum cups which are engaged by a roller for compressing the heads to distort the vacuum cups to expel the air therefrom as it rolls over the surface to be massaged, whereupon a vacuum is produced as the cups return to their natural positions to draw upon the skin of the part massaged.

A further object is the provision of a massage device which may be grasped by the hand of a user and operated upon his own body or that of another without tiring results.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a perspective view of my improved massage device strapped to the wrist of a user.

Figure 2 is a vertical longitudinal sectional view on the line 2—2 of Figure 1.

Figure 3 is a vertical transverse sectional view on the line 3—3 of Figure 2.

Referring to the drawings by reference characters, the numeral 10 designates my improved massage device in its entirety which includes a cylindrical casing or shell 11 having end walls 12 while the side wall is provided with spaced openings 13 arranged in annular rows therearound. Surrounding the cylinder is a yieldable elastic sleeve 14 which is cemented to the cylinder for turning therewith, while the outer surface of the rubber sleeve is provided with annular arranged rows of vacuum cups or recesses 15. Flexible heads or projections 16 extend inwardly behind the respective vacuum cups and pass through the openings 13 in the cylinder to extend within the same. Annular metal bands 17 encircle the sleeve between the rows of vacuum cups to aid in preventing accidental separation of the rubber sleeve from the cylinder. The metal bands lie below the plane of the outer edges of the vacuum cups so as not to touch the skin to be massaged during use of the device.

Vulcanized or cemented to the heads 16 is a continuous fabric strip 18 which is slack between the heads to allow a limited spreading movement to the heads and for preventing the pressing roller 19 from becoming stuck between two adjacent rows of heads.

Journalled in the end walls 12 axially thereof is a shaft 20 having links 21 fixedly mounted thereon adjacent the inner sides of the end walls and which links serve as depending bearings for a shaft 22 on which the roller 19 is turnably mounted and which rides over the yieldable heads protected by the fabric covering for successively collapsing the vacuum cups 15. As the roller successively moves into engagement with the heads, the fabric covering becomes taut as shown in

Figure 3 and limits the flattening of the heads.

5 Fixed to the exteriorly projecting ends of the shaft 20 are the angular parallel legs 23 of a yoke 24, the yoke portion being twisted at right angle to lie flat against the wrist of the arm of a user. A cushion pad 24' is provided on the top of the yoke for preventing the wrist from resting directly on the metal yoke. The yoke carries a buckle strap 25 by which the device may be strapped to the wrist, while a hand grip 26 is supported by the legs 23 at the bends therein which is 10 suitably spaced from the strap to comfortably receive the hand as shown in Figure 1 15 of the drawings.

In use, the device is applied to the wrist of a user in the manner just described and the hand grip 26 is grasped. The natural massage position is shown in Figure 3 of the 20 drawing, wherein the axis of the roller 19 is to one side of the vertical axis of the axis of the cylinder, so that as the device is rolled over the flesh to be massaged, the roller acts 25 upon the heads just prior to engagement of the vacuum cups with the surface to be massaged to flatten the vacuum cups and expel the air therefrom. As the vacuum cups engage 30 the flesh and the roller releases the heads, the resilient nature of the same returns them to normal position and when returning to normal position, the same suck upon the flesh by reason of the vacuum produced thereby. This suction tends to stimulate the tissues of 35 the skin or flesh to induce blood circulation and maintain the user in a healthy condition. By lining the interior with a fabric covering, the roller is prevented from direct contact with the heads, which prevents wearing and breaking of the same.

40 While I have described what I deem to be the most desirable embodiment of my invention, it is obvious that many of the details may be varied without in any way departing 45 from the spirit of my invention, and I therefore do not limit myself to the exact details of construction herein set forth nor to anything less than the whole of my invention limited only by the appended claims.

50 What is claimed as new is:—

1. A massage device comprising a cylindrical casing, an outer sleeve carried thereby and having yieldable vacuum cups provided 55 therein, yieldable heads disposed behind said vacuum cups and extending inwardly through said cylindrical casing, handle means, and free turning roller means within said casing for successively engaging said heads for expelling air from said vacuum cups as the device is rolled over a surface to be massaged.

60 2. A massage device comprising a cylindrical casing, an outer sleeve carried thereby and having yieldable vacuum cups provided 65 therein, yieldable heads disposed behind said vacuum cups and extending inwardly through

said cylindrical casing, a continuous flexible fabric lining fixedly attached to said heads, handle means, and roller means within said casing for movement of said fabric lining for successively compressing said heads for expelling air from said vacuum cups as the device is rolled over a surface to be massaged.

70 3. A massage device comprising a hollow cylindrical casing, a sleeve on the exterior thereof, yieldable vacuum cups arranged in the exterior thereof, yieldable heads extending inwardly through said casing and respectively disposed behind said vacuum cups, a roller journaled within said casing for successively compressing said yieldable heads to distort said vacuum cups to expel air therefrom, and handle means on which the roller is mounted and by which the device may be rolled over the surface to be massaged.

75 4. A massage device comprising a hollow cylindrical casing, a yieldable rubber sleeve on the exterior thereof having vacuum cups opening onto the exterior surface, inwardly projecting yieldable heads passing through openings in said casing to extend beyond the inner wall thereof, a shaft journaled in the end walls of said casing, depending arms fixed to said shaft, a roller journaled in said arms for successively compressing said heads to distort said vacuum cups to expel air therefrom, and a handle member fixedly connected to the ends of said shaft.

80 5. A massage device comprising a hollow cylindrical casing, a yieldable rubber sleeve on the exterior thereof having vacuum cups opening onto the exterior surface, inwardly projecting yieldable heads passing through openings in said casing to extend beyond the inner wall thereof, a shaft journaled in the end walls of said casing, depending arms fixed to said shaft, a roller journaled in said arms for successively compressing said heads to distort said vacuum cups to expel air therefrom, a continuous flexible lining connected to said heads and bridging the same, and a handle member fixedly connected to the ends of said shaft.

85 100 6. A massage device comprising a hollow cylindrical casing, a yieldable rubber sleeve on the exterior thereof having vacuum cups opening onto the exterior surface, inwardly projecting yieldable heads passing through openings in said casing to extend beyond the inner wall thereof, a shaft journaled in the end walls of said casing, depending arms fixed to said shaft, a roller journaled in said arms for successively compressing said heads to distort said vacuum cups to expel air therefrom, a yoke having its free ends fixedly connected to the ends of said shaft, a hand grip bridging the legs of said yoke, and a wrist strap provided on the closed end of said yoke by which the device may be strapped to the wrist of the user.

90 110 7. A massage device consisting of a yoke

equipped with a free turning handle, a hollow cylinder mounted to rotate on the yoke, said cylinder having a series of openings in its wall, a rubber sleeve mounted on the cylinder and formed with a series of external 5 vacuum cups and heads integral therewith projecting through said cylinder openings, and a free turning roller mounted in the cylinder to rotate by friction against the heads when the cylinder is rolled against a surface 10 to be massaged.

In testimony whereof I have affixed my signature.

LORENZO ARRANZ.
